(57) **CLAIM**

The ornamental design for a foldable power adapter and stand, as shown and described.

DESCRIPTION

FIG. 1 is a front perspective view of the foldable power adapter and stand showing my new design;

FIG. 2 is a front elevational view of the foldable power adapter and stand of FIG. 1;

FIG. 3 is a left elevational view of the foldable power adapter and stand of FIG. 1;

FIG. 4 is a rear elevational view of the foldable power adapter and stand of FIG. 1;

FIG. 5 is a right elevational view of the foldable power adapter and stand of FIG. 1;

FIG. 6 is a top plan view of the foldable power adapter and stand of FIG. 1;

FIG. 7 is a bottom plan view of the foldable power adapter and stand of FIG. 1;

FIG. 8 is a front perspective view of the foldable power adapter and stand of FIG. 1 shown in use and in open condition;

FIG. 9 is a front elevational view of the foldable power adapter and stand of FIG. 8;

FIG. 10 is a left elevational view of the foldable power adapter and stand of FIG. 8;

FIG. 11 is a rear elevational view of the foldable power adapter and stand of FIG. 8;

FIG. 12 is a right elevational view of the foldable power adapter and stand of FIG. 8;

FIG. 13 is a top plan view of the foldable power adapter and stand of FIG. 8; and,

FIG. 14 is a bottom plan view of the foldable power adapter and stand of FIG. 8.

The broken lines showing a portable media player are for illustrative purposes and form no part of the claimed design.
